UNITED STATES PATENT OFFICE.

HAROLD M. STURGEON, OF ERIE, PENNSYLVANIA.

HAMMER.

1,300,511.

Specification of Letters Patent. Patented Apr. 15, 1919.

Application filed July 28, 1917. Serial No. 182,927.

To all whom it may concern:

Be it known that I, HAROLD M. STURGEON, a citizen of the United States, residing at Erie, in the county of Erie, and State of Pennsylvania, have invented certain new and useful Improvements in Hammers; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to mechanical hammers, and the object thereof is to provide a hammer mechanism which can be operated by an electric motor or other source of power, and in which the length of the stroke 20 of the hammer and the power thereof is controlled by the pressure which the operator exerts against the work.

The features of my invention will be hereinafter fully described and pointed out, and 25 are illustrated in the accompanying drawings, in which:

Figure 1, is a side elevation of my improved hammer mechanism.

Fig. 2, is a longitudinal central section of 30 the same.

Fig. 3, is a like section of a portion of the shell, showing mechanism therein in elevation in position for a partial stroke of the hammer.

35 Fig. 4, is a like view showing the hammer in position for a full stroke.

Fig. 5, is a transverse section on the line 5—5 in Fig. 2.

Fig. 6, is a transverse section on the line 40 6—6 in Fig. 3.

Fig. 7, is a transverse section on the line 7—7 in Fig. 4.

In these drawings A indicates the shell of 45 the hammer frame, the ends of which are closed by means of the closures A' and A².

The closure A' is provided with an externally threaded boss A³, which has a longitudinal opening therethrough in which is placed a shaft B which is suitably connected 50 with a flexible shaft B' leading to a suitable source of power, through a handle B² screwed upon the boss A³. The shaft B is provided with a thrust shoulder b which engages the inner side of the closure A'.

55 Within the shell A is a hollow hammer C closed at one end, said hammer C being pre-

vented from rotating in the shell A by means of a longitudinal bar c (see Fig. 5) secured against the inner wall of the shell A and working in a longitudinal slot in the side of 60 the hammer C. The hammer C is provided with a diagonal slot C' through the wall thereof, and substantially one-half of the circumference of the hammer C.

Within the hammer C is placed a thimble-like shell D in the wall of which is secured the axle D' of a pair of rollers d and d', the roller d being in the diagonal slot C' in the hammer C. Within the thimble-like shell D there is an annular helical cam E which is 65

adapted to engage the roller d' as herein-after described, said cam being provided with a hollow shaft E', which slidably fits over the inner end of the shaft B, said hollow shaft having slots e e (see Figs. 3 and 4) 70

through opposite walls thereof to receive the ends of a transverse pin b' (see Fig. 2) secured through the inner end of the shaft B, and within the hollow shaft E' is a spring 75

E² adapted to maintain the cam E and its 80 hollow shaft in its most extended position, as shown in Fig. 2. The bottom of the thimble-like shell D is provided with a square hole d² therethrough, and the closed end of the hammer is provided with a round 85

hole c' therethrough. The closure A² is provided with a boss A⁴ having a central opening therethrough, in which there is slidably and rotatably mounted a short shaft F which is provided with a helical slot f in which a 90

roller f', mounted upon a pivot screw f², secured in the wall of the boss A⁴ operates.

Integrally secured to the inner end of the shaft F is a square bar G which extends inwardly through the round opening c' in the 95 end of the hammer C and through the square opening in the thimble D when it is provided with a washer G' which is provided with a square recess adapted to fit over the end of the square bar G, said washer G' engaging 100

the lower end of the cam E, the spring E² operating to force the cam E downward against the washer G' and thereby maintain the square bar G and shaft F in their normal position as shown in Fig. 2.

105 Upon the boss A⁴ is secured a tapering sleeve H and in the outer end of the sleeve H is slidably mounted a tool stock J which is prevented from rotating therein by means of a spline J' operating in a groove in the 110 sleeve H. The inner end of the tool stock J is provided with a stud-post j (see Fig. 4)

which enters a socket in the outer end of the shaft F and the outer end of the tool stock J is provided with a tool receiving socket as shown in Fig. 2.

- 5 In operation the cam E is caused to rotate in the direction of the arrow thereon in Fig. 2, and the tool secured in the tool stock is pressed against the work, which pressure forces the tool stock J and shaft F and 10 square bar G inwardly thereby forcing the cam E upwardly so that the cam surface thereon will engage the roller d' and at the same time the helical slot f in the shaft F causes the shaft F and square bar G to turn 15 in the same direction, as the cam E is rotating, thereby revolving the thimble D which carries the roller d around in the diagonal slot C' in the wall of the hammer C a quarter of a revolution, (as shown in Figs. 3 and 6) 20 or a half revolution, (as shown in Figs. 4 and 7) when the tool stock J is pushed in as far as it will go.

When the mechanism is in the position shown in Figs. 2 and 5, the cam will not lift 25 the hammer C and thimble D; when in the position shown in Figs. 3 and 6, the cam lifts the hammer one-half of a stroke; and when in the position shown in Figs. 4 and 30 7, the cam lifts the hammer the full length of the stroke. Between the closure A' and the hammer C there is a spring K the inner 35 end of which enters a thimble K' within the open end of the hammer and is provided with a radial flange which overlaps the end of the hammer, and with an inturned flange at the other end thereof upon which the spring K is seated. The spring K operates to force the hammer C forward when the 40 roller d' rolls off of the apex of the cam E and the tension of said spring is increased as the hammer C is forced upward in the shell A by the tool stock and shaft F shifting the roller d around in the diagonal slot C'.

- 45 The hammer C when in the position shown in Fig. 4 has compressed the spring K as shown, and then is raised the full length of its stroke by the cam E away from the shaft F and the spring K when the roller 50 d' passes the apex of the cam E drives the hammer forward against the shaft F through which the force of the blow is imparted to the tool stock J. The rotation of the shaft F and bar G causes the thimble 55 D to rotate within the hammer C which rotation carries the rollers d and d' around the axis of the hammer, and the diagonal slot C' causes said rollers to move longitudinally toward the front end of the hammer so that 60 as the tool stock J and shaft F and the cam E are pushed inward, the hammer C also moves inward, but the normal position, longitudinally, of the rollers d and d' remains the same, so that as the cam E moves in- 65 ward, the length of the stroke of the ham-

mer is increased by reason of the cam E engaging the roller d earlier in its rotation.

Having thus fully described my invention so as to enable others to utilize the same, I do not desire to be limited to the exact construction and arrangement shown, as many changes can be made therein without departing from the scope of my invention as defined in the claims.

Therefore what I claim as new and desire to secure by Letters Patent is:

1. In a device of the class described, a frame, a hollow spring-pressed reciprocating hammer, a helical cam within said hammer, means co-engaging said hammer and said cam, a longitudinally movable tool-stock in said frame to receive the blows of said hammer, means operated by the longitudinal movement of said tool-stock to control the length of the stroke of said hammer, and means to rotate said cam, substantially as set forth.

2. In a device of the class described, a frame, a hollow spring-pressed reciprocating hammer therein, a spring-pressed, rotatable and longitudinally movable helical cam within said hammer, longitudinally movable means adapted to co-engage said hammer and said cam, a longitudinally slidable tool-stock mounted in said frame, means mounted between said tool-stock and said hammer adapted to be operated by the longitudinal movement of said tool-stock to control the longitudinal position of said cam with relation to said hammer, and means to cause said cam to rotate, substantially as set forth.

3. In a device of the class described, a frame, a hollow spring-pressed reciprocating hammer non-rotatable in said frame having a helical slot in the wall thereof, and a round opening in the front end thereof, a thimble rotatably mounted in said hammer, and having an opening in the front end thereof, a stud post secured in the wall of said thimble and projecting inwardly therefrom and outwardly into the helical slot in said hammer, rollers on the inner and outer ends of said stud-post, a driven shaft mounted in said frame, a spring-pressed, helical cam within said thimble slidably and non-rotatably secured on said driven shaft and adapted to engage the stud-roller on the inside of said thimble, means to rotate said driven shaft, a slidable member mounted in said frame and adapted to receive blows from said hammer, means to cause said slidable member to rotate during its longitudinal movement, means secured to said slidable member and extending through said round opening in the front end of said hammer, and non-rotatably through the opening in said thimble and engaging the front end of said helical cam, whereby said thimble is caused to rotate within said hammer and

said helical cam is moved longitudinally therein, and a tool-stock slidably secured in said frame and engaged by said slidable member, substantially as set forth.

5 4. In a device of the class described, a frame, a hollow, spring-pressed reciprocating hammer having an opening in its front end slidably and non-rotatably mounted in said frame, said hammer having a helical 10 slot in the wall thereof, a thimble rotatably mounted in said hammer, a stud-roller pivoted on the exterior of said thimble and projecting into said helical slot, a stud-roller pivoted on the interior wall of said thimble, 15 a driven shaft axially mounted in said frame, a helical cam in said thimble adapted to engage the stud roller on the interior of said thimble, a hollow shaft for said cam and telescoping over said driven shaft, a 20 spring in said hollow-shaft to normally maintain said cam in its outermost position, a short shaft slidably mounted in said frame

in axial alinement with said hammer, a bar axially secured on said short shaft extending inwardly through the opening in the front 25 end of said hammer and slidably and non-rotatably passing through the bottom of said thimble and contacting against the end of said helical cam, means to cause said short shaft to rotate during its longitudinal movement, and a tool-stock slidably mounted in the frame in axial alinement with said short shaft and hammer, and contacting against said short shaft, whereby, as the tool-stock 30 is caused to move inwardly by pressure 35 against the work, said helical cam is moved longitudinally and said thimble caused to rotate within said hammer to move said stud-rollers forward in the helical slot in said hammer to increase the length of the 40 stroke of said hammer, substantially as set forth.

In testimony whereof I affix my signature.
HAROLD M. STURGEON.
